Filed May 13, 1964, Ser. No. 79,977

Term of patent 14 years

(Cl. D90—20)

FIG. 1

FIG. 2

FIG. 3

FIG. 1 is a perspective view of a tire showing the new design, it being understood that the tread portion is repeated throughout the circumference of the tire and that the shoulder design is repeated throughout the circumference of the shoulder, the opposite side of the tire being substantially like the side shown;

FIG. 2 is a fragmentary transverse sectional view taken through the tire substantially on the plane indicated by the line 2—2 of FIG. 1; and

FIG. 3 is an enlarged fragmentary side elevational view. I claim:

The ornamental design for a tire, substantially as shown and described.
